(57) **CLAIM**

The ornamental design for a control panel, as shown and described.

DESCRIPTION

FIG. 1 is an isometric projection of a control panel of the design according to a first embodiment of the invention (a faceplate, which does not form part of the invention, is shown in phantom);

FIG. 2 is a front elevational view of the control panel of FIG. 1 (a faceplate, which does not form part of the invention, is shown in phantom);

FIG. 3 is a bottom plan view of the control panel of FIG. 1 (a faceplate, which does not form part of the invention, is shown in phantom);

FIG. 4 is a top plan view of the control panel of FIG. 1 (a faceplate, which does not form part of the invention, is shown in phantom);

FIG. 5 is a right side elevational view of the control panel of FIG. 1 (a faceplate, which does not form part of the invention, is shown in phantom);

FIG. 6 is a left side elevational view of the control panel of FIG. 1 (a faceplate, which does not form part of the invention, is shown in phantom);

FIG. 7 is an isometric projection of a control panel of the design according to a second embodiment of the invention (a faceplate, which does not form part of the invention, is shown in phantom);

FIG. 8 is a front elevational view of the control panel of FIG. 7 (a faceplate, which does not form part of the invention, is shown in phantom);

FIG. 9 is a bottom plan view of the control panel of FIG. 7 (a faceplate, which does not form part of the invention, is shown in phantom);

FIG. 10 is a top plan view of the control panel of FIG. 7 (a faceplate, which does not form part of the invention, is shown in phantom);

FIG. 11 is a right side elevational view of the control panel of FIG. 7 (a faceplate, which does not form part of the invention, is shown in phantom);

FIG. 12 is a left side elevational view of the control panel of FIG. 7 (a faceplate, which does not form part of the invention, is shown in phantom);

FIG. 13 is an isometric projection of the control panel of the design according to a third embodiment of the invention (a faceplate, which does not form part of the invention, is shown in phantom);

FIG. 14 is a front elevational view of the control panel of **FIG. 13** (a faceplate, which does not form part of the invention, is shown in phantom);

FIG. 15 is a bottom plan view of the control panel of **FIG. 13** (a faceplate, which does not form part of the invention, is shown in phantom);

FIG. 16 is a top plan view of the control panel of **FIG. 13** (a faceplate, which does not form part of the invention, is shown in phantom);

FIG. 17 is a right side elevational view of the control panel of **FIG. 13** (a faceplate, which does not form part of the invention, is shown in phantom);

FIG. 18 is a left side elevational view of the control panel of **FIG. 13** (a faceplate, which does not form part of the invention, is shown in phantom);

FIG. 19 is an isometric projection of a control panel of the design according to a fourth embodiment of the invention (a faceplate, which does not form part of the invention, is shown in phantom);

FIG. 20 is a front elevational view of the control panel of **FIG. 19** (a faceplate, which does not form part of the invention, is shown in phantom);

FIG. 21 is a bottom plan view of the control panel of **FIG. 19** (a faceplate, which does not form part of the invention, is shown in phantom);

FIG. 22 is a top plan view of the control panel of **FIG. 19** (a faceplate, which does not form part of the invention, is shown in phantom);

FIG. 23 is a right side elevational view of the control panel of **FIG. 19** (a faceplate, which does not form part of the invention, is shown in phantom);

FIG. 24 is a left side elevational view of the control panel of **FIG. 19** (a faceplate, which does not form part of the invention, is shown in phantom);

FIG. 25 is an isometric projection of a control panel of the design according to a fifth embodiment of the invention (a faceplate, which does not form part of the invention, is shown in phantom);

FIG. 26 is a front elevational view of the control panel of **FIG. 25** (a faceplate, which does not form part of the invention, is shown in phantom);

FIG. 27 is a bottom plan view of the control panel of **FIG. 25** (a faceplate, which does not form part of the invention, is shown in phantom);

FIG. 28 is a top plan view of the control panel of **FIG. 25** (a faceplate, which does not form part of the invention, is shown in phantom);

FIG. 29 is a right side elevational view of the control panel of **FIG. 25** (a faceplate, which does not form part of the invention, is shown in phantom); and,

FIG. 30 is a left side elevational view of the control panel of **FIG. 25** (a faceplate, which does not form part of the invention, is shown in phantom).

The rear part of the control panel of the figures does not constitute part of the invention and, therefore has been omitted from the drawings.
